CLAIM

The ornamental design for molded surface of a concrete product, as shown and described.

DESCRIPTION

FIG. 1 is a front elevational view of a molded surface of a concrete product according to our new design;

FIG. 2 is a right side elevational view thereof;

FIG. 3 is a left side elevational view thereof;

FIG. 4 is a top view thereof;

FIG. 5 is a bottom view thereof; and,

FIG. 6 is a front perspective view thereof.

The broken lines in drawing views are included for the purpose of illustrating portions of the concrete product that form no part of the claimed design.

1 Claim, 6 Drawing Sheets
